UNITED STATES PATENT OFFICE.

BAMFORD ELLIOTT, OF WORCESTER, MASSACHUSETTS, ASSIGNOR TO WARREN LEATHER GOODS COMPANY, OF WORCESTER, MASSACHUSETTS, A CORPORATION OF MASSACHUSETTS.

HAND LUGGAGE.

Application filed August 11, 1924. Serial No. 731,304.

This invention relates to hand luggage of the type in which an inner frame or casing is covered with leather or similar sheet material of substantial thickness. 5 Much difficulty has been experienced in the past in providing a firm and satisfactory seam at the corners of such luggage. The seams previously used were often of weak construction and left thin unprotected edges 10 of the covering material which were very easily damaged.

My invention relates to the provision of an improved corner construction and seam for such articles, by which the durability 15 of the articles is much increased and the appearance is also improved.

My invention further relates to arrangements and combinations of parts which will be hereinafter described and more particularly pointed out in the appended claims. 20

A preferred form of the invention is shown in the drawings in which

Fig. 1 is a perspective view of a suit-case embodying my improvements;

25 Fig. 2 is an enlarged detail view of one corner thereof; and

Fig. 3 is a detail sectional view taken along the line 3—3 in Fig. 2.

Referring to the drawings, I have shown 30 a suit-case having an inner box or frame 10 formed of wood or fibre or some other firm and suitable material. A layer 11 of leather or other covering material of substantial thickness is secured to an end face 35 of the suit-case frame or casing 10 and the edge of the material 11 is extended at full thickness to the extreme edge or corner of the casing. The material 11 may be secured to the casing by glue or cement or in any 40 other convenient manner.

A second layer 12 of covering material is applied to the side and top faces of the casing 10 and the edge portion 13 thereof is extended beyond the corner of the casing 45 10 and beyond the layer of covering material 11 and is folded down over the edge of the material 11, as clearly shown in Figs. 2 and 3. The layer 12 may be cemented or otherwise secured in this position.

50 After being thus folded and secured about the corner of the suit-case, a row of stitching 14 is inserted diagonally through the corner of the suit-case, the stitches passing through the body of the covering material 55 12, through the edge portion of the covering

material 11, and through the folded edge portion 13 of the material 12. In this way, the covering material 12 is firmly secured over and around the edge of the material 11, and the stitches in their intermediate portions pass directly through the edge of the material 11. Preferably the material 11 is of full thickness at its extreme edge. 60

A suit-case or other article of hand luggage having its corner seams formed as 65 shown and described is much improved in its general appearance and the corner seams are excellently adapted to resist rough usage and to maintain their pleasing appearance after long service. 70

Having thus described my invention and the advantages thereof, I do not wish to be limited to the details herein disclosed otherwise than as set forth in the claims, 75 but what I claim is:—

1. In hand luggage, a casing formed of rigid frame members meeting in a corner, a layer of covering material of substantial thickness secured to one face of said casing and extending to said corner, a second layer 80 of covering material of substantial thickness secured to a second face of said casing and extending beyond said corner to overlap said first mentioned covering material, and a row of stitches extending diagonally 85 through the body portion and the overlapping portion of said second layer of covering material and also extending through the edge portion of said first layer of covering material externally of said frame members. 90

2. In hand luggage having surfaces meeting in a corner, a layer of covering material of substantial thickness secured to one of said surfaces and extending to said corner, a second layer of covering material of substantial thickness secured to a second surface of said luggage, extending beyond said corner and folded to overlap the edge portion of said first layer of covering material, and a row of stitches extending diagonally 100 through the body portion and the overlapping portion of said second layer of covering material and through the edge portion of said first layer of material, externally of said surfaces. 105

3. In hand luggage having surfaces meeting in a corner, a layer of covering material of substantial thickness secured to one of said surfaces and extending to said corner, a second layer of covering material of sub- 110

stantial thickness secured to a second surface of said luggage, extending beyond said corner and folded to overlap the edge portion of said first layer of covering material, and a row of stitches extending diagonally through the body portion and the overlapping portion of said second layer of material and through the edge portion of said first layer of material, the edge portion of the first layer of material being of the full thickness of said material, externally of said surfaces.

4. In hand luggage, a frame, a layer of covering material secured to one face thereof, a second layer of covering material secured to another face thereof, a seam of substantial thickness formed by overlapping

said layers at a corner of the frame and seam stitches extending diagonally through the edge portions of each layer and the body portion of the second layer, externally of said frame.

5. In hand luggage, a rigid box frame and a covering therefor having edges overlapping at a corner of the frame, means to fasten the covering to the frame, and seam stitches extending diagonally through the overlapping edge portions and through the body portion of said covering, externally of said frame.

In testimony whereof I have hereunto affixed my signature.

BAMFORD ELLIOTT.
